UNITED STATES PATENT OFFICE

VAN R. DEAN, OF SPRINGFIELD, MISSOURI

ADJUSTABLE HAME FASTENER

Application filed August 15, 1930. Serial No. 475,487.

This invention relates to harness and more particularly to a connection or fastener by means of which the upper ends of a pair of hames may be connected and supported in their proper positions against side portions of a collar.

One object of the invention is to provide a fastener or connection which may be longitudinally adjusted in order to accommodate itself to the size of the collar to which the hames are to be applied and further to so form the device that when the hames are in place they will be firmly held and prevented from moving out of their proper positions.

Another object of the invention is to provide a device of this character so constructed that when the hames are removed from the collar the connecting device for their upper ends cannot become twisted and allow the hames to tangle.

Another object of the invention is to so form this improved connecting device that it will fit properly when resting upon a collar and also to form the device of such shape in cross section that it will not be liable to cut into the collar and cause the collar to be quickly worn out.

Another object of the invention is to not only prevent a collar from becoming worn but also prevent a horse's neck from being injured by pinching.

The invention is illustrated in the accompanying drawing, wherein

Figure 1 is a view in elevation of a pair of hames having their upper ends connected by the improved fastener,

Fig. 2 is a transverse sectional view through the improved fastener taken on the line 2-2 of Fig. 1,

Fig. 3 is a perspective view of a tubular member forming a portion of the fastener, and

Fig. 4 is a perspective view of a second member which is slidably received in the tubular member shown in Fig. 3.

The improved adjustable fastener or connection has been shown applied to the upper ends of a pair of hames in Figure 1. These hames, which are indicated by the numeral 1, are of a conventional construc-

tion and near their upper ends carry clevises 2 which are secured by fasteners 3 passed through the hames and extend inwardly from the hames. The fastener or connection consists of companion members 4 and 5 which are formed of strong metal and it

should be noted that they curve longitudinally so that the fastener may rest upon the upper portion of a collar and fit properly thereon when the hames are applied to the collar.

The member 4 consists of a tube open at its ends in order to receive the member 5 and side walls of this tubular member are formed with openings 6 disposed in opposed relation to each other, as shown in Figure 2. The outer end of the tube is cut diagonally, as shown in Figure 3, in order to form a tongue which extends longitudinally thereof and this tongue is bent upwardly and inwardly to form a bill or hook

7 adapted to engage through the clevis 2 of one of the hames. The member 5 which telescopes into the member 4 through the inner end thereof is preferably formed from a solid bar, although a tube of the proper diameter may be used. This member has its outer end portion flattened to form a tongue extending longitudinally of the bar

and the tongue is bent upwardly and inwardly to form a bill or hook 8 similar in shape to the bill or hook 7 and intended to engage through the clevis of the other hame.

An opening 9 is formed near the inner end of the member 5 and by sliding the two members longitudinally relative to each other the opening 9 may be disposed in position

to register with a selected set of openings 6 in the member 4 so that a cotter key or other suitable removable fastener 10 may be passed through the registering openings and firmly but releasably secure the two members in a set position. Therefore, the length of the connection may be controlled and the device

permitted to accommodate itself to the size of collar to which it is to be applied. By referring to Figure 2, it will be seen that the two members 4 and 5 are non-circular in cross section and have flat upper and lower faces which merge into their side faces. Therefore, rounded corners are formed and

100

there will be no danger of a collar being quickly worn through by rough edges.

Having thus described the invention, I claim:

5. A hame connection comprising a tubular open-ended female member substantially elliptical in cross section and curved longitudinally to conform to the shape of a horse collar, said female member having its outer 10 end cut diagonally and bent upwardly and inwardly in spaced relation to the diagonal cut to form a clevis engaging hook, there being uniformly spaced transverse openings formed in said female member and centered 15 between the upper and lower faces thereof, and the outer walls of said female member being smooth and unobstructed throughout their entire extent, a correspondingly shaped male member adjustably fitted with 20 in the female member and having one end thereof provided with a clevis engaging hook and its other end formed with a single transverse opening adapted to register with any one of the openings in the female member, 25 and a fastening device extending through registering openings in said members for holding the same in adjusted position.

In testimony whereof I affix my signature.
